UNITED STATES PATENT OFFICE

WALTER H. WEEKS, OF LAWRENCE, LONG ISLAND, NEW YORK, ASSIGNOR, BY MESNE ASSIGNMENTS, TO FEDERAL DISTRIBUTING CO. INC., OF NEWARK, NEW JERSEY, A CORPORATION OF NEW JERSEY

INCANDESCENT LAMP

Application filed August 11, 1930. Serial No. 474,367.

My present invention relates to the incandescent lamp art and more particularly to improvements in incandescent lamps comprising what may be called a combination 5 filament which is adapted to be burned at the ordinary house lighting voltages but which is capable by means of the arrangement embodied in the lamp of being burned not only at the maximum wattage to which 10 the lamp is adapted but also at lower wattages at the same voltage and without loss of efficiency.

The invention may be more fully understood by reference to the drawings forming 15 part of this specification, which show specific preferred embodiments of the invention, illustrative thereof but without limiting the invention thereto.

In said drawings, Fig. 1 shows diagrammatically a lamp embodying one form of the invention; Figs. 1^a and 1^b are views of the insulating button 11 detached from the lamp; and Fig. 2 is a diagrammatic view of another embodiment of the invention using wiping 25 contacts.

The drawings illustrate a type of lamp within this invention having a combination filament adapted to burn at a given predetermined wattage, the filament being enclosed 30 in a bulb which may be either evacuated or have a gaseous atmosphere.

Thus, assuming that the lamp illustrated in Fig. 1 is designed to operate on a 110 volt circuit at 50 watts for each half of the filament, it is possible to operate it selectively 35 either at 100 watts or 50 watts on the same voltage by the simple act of screwing the lamp-base to a greater or less distance into the socket.

Fig. 1 shows diagrammatically one embodiment of the invention. In this figure, I happen to show a three-stage lamp,—that is to say, a lamp operable at three different degrees of illumination. However, the principle is the same regardless of whether there 45 be two, three or more stages.

In this lamp, a button 11 made of porcelain or other suitable insulating material is stationarily mounted within the shell of the lamp-base with its lower portion project-

ing through the usual large opening in the bottom of said shell. This button has an axial hole through it leading into a recess of larger diameter countersunk into the top of the button, meaning the portion thereof 55 that is inside the base of the lamp. A headed metal pin 12 is contained in this recess and axial hole in the button and is axially movable therein. Metallic spring contacts 13, 14, 15 secured to the top of the button at its periphery project radially inwardly so that their free ends overlie one another and the head of the pin 12. Said spring contacts are all supported at different levels so that normally they are all out of contact with and 60 insulated from one another. One preferred way to accomplish this is that illustrated 65 consisting in forming the top of the insulating button 11 so that it presents different steps or levels 11^a, 11^b, 11^c adapted to support the respective flat spring contacts at the described different levels. Different views 70 of this button 11 detached from the lamp are shown in Figs. 1^a and 1^b.

The filament of the lamp in Fig. 1 is a 75 combination filament designated in general by the numeral 16 and comprising three parts 16^a, 16^b, 16^c. These different parts may be designed to burn at different or the same 80 wattages but the same voltage to give different degrees of illumination. All of these parts of the combination filament 16 are connected together at one end to a lead-wire 17 soldered to a metallic shell 18 of the lamp-base. At its other end, each individual part 85 of the filament is connected to an individual lead-wire 19^a, 19^b, 19^c respectively. These lead-wires in turn are severally electrically connected to the previously described spring contacts 13, 14, 15.

Upon screwing this lamp into an ordinary lamp socket, the projecting free end of the pin 12 coming in contact with the center contact of the socket is forced inwardly to bring its head into engagement with the first or lowermost spring contact 13. This adjustment of the lamp will serve to burn a 95 part of the filament designated 16^a which, for example, may be a ten watt filament operating on 110 volts. If a different degree of 100

illumination be desired, the lamp-base will then be screwed a trifle farther into the socket until the pin has pressed the first spring contact against the second spring contact 14, whereupon the part 16^b of the filament will also burn. This part 16^b, for example, may be a 25 watt filament operating at 110 volts, thereby adding that much more to the illumination. To get still more illumination, the part 16^c also may be burned along with 16^a and 16^b by screwing the lamp still farther into its socket until the pin has forced the first and second contacts into engagement with the third spring contact 15. This last named part 16^c of the filament may also be a 25 watt filament operating at 110 volts.

Fig. 2 shows diagrammatically another form of the invention differing in having wiping contacts. Here the lamp-base comprises the metallic screw-threaded shell 20 secured to the porcelain button or cap 21. Slidably in an axial hole in the latter is a pin 22 headed at both ends 22^a and 22^b. 23^a, 23^b and 23^c are spring contacts insulated from one another and suitably supported by the porcelain button at different levels within the shell. These radially arranged contacts have their free ends directed towards the axis of the lamp-base so as to be wiped one after the other by the head 22^a of the pin 22 when forced inwardly by screwing the lamp-base into its socket with the head 22^b of the pin in engagement with the center contact of the socket. 24 is a spiral spring surrounding the pin between its outer head 22^b and the porcelain button 21, said spring being strong enough to withdraw the inner head 22^a of the pin out of contact successively with the contacts 23^a, 23^b and 23^c as fast as permitted by the act of unscrewing the lamp-base from its socket.

The diagram Fig. 2 also indicates the circuit connections to the three part combination filament whose parts are designated respectively 25^a, 25^b and 25^c. All of these are shown joined together at one end which is connected by lead-wire 26 to the shell 20. Their other ends are respectively connected by lead-wires 27^a, 27^b and 27^c to the aforesaid contacts 23^a, 23^b and 23^c.

In the particular illustration Fig. 2, as the lamp-base is screwed into its socket, filament 25^a will first light up, due to the electrical connection made between the head 22^a of the pin and the wiping contact 23^a. This may be a 10 watt filament. Screwng in the lamp-base still further causes the head 22^a of the pin to leave the contact 23^a to de-energize this 10 watt part 25^a of the filament and to come into contact with the next wiping contact 23^b. This causes the second part 25^b of the filament to light, which may be a 25 watt filament. Finally, screwing in the lamp-base still further does not deenergize said filament 25^b but additionally ener-

gizes filament 25^c due to the fact that the two contacts 23^b and 23^c purposely, but, of course, not necessarily, are located nearly enough at the same level so that the head 22^a of the pin can contact both of them at the same time. In this case, if the filament 25^c be a 25 watt filament, then the total illumination will be that of a 50 watt lamp.

It will be understood that other changes and modifications additional to those already indicated may be made in the particular embodiments of the invention without departing from the scope and spirit thereof or the scope and spirit of the claims.

What I claim is:

1. An incandescent lamp comprising a combination filament; a plurality of spring contacts electrically connected with the combination filament to make its different parts operative, said contacts being at different levels within the base of the lamp; an electrically conductive pin supported for axial reciprocation in the end of said base adapted to be pressed by the center contact of a lamp socket in screwing the base into the socket to make electrical connection with the lowermost spring contact and then as the plug is screwed still further into the socket to make electrical connection successively with the other contacts.

2. A base for an incandescent lamp comprising a metallic shell, insulating material supported by said shell and having an axial hole therethrough; a pin supported in said hole with an end operatively projecting below said insulating material, the top of said insulating material within the shell being formed with portions raised to different levels relatively to each other; and contacts mounted on said portions at the different levels with their free ends projecting towards the axis of the shell to overlie the aforesaid pin.

3. A base for an incandescent lamp comprising a metallic shell, insulating material supported by said shell and having an axial hole therethrough; a pin supported in said hole with an end operatively projecting below said insulating material, said pin having a conducting head within said shell; contacts insulated from each other and supported at different levels within said lamp base to come into wiping contact with the head of said pin when forced in and out; and a spring tending to force the pin into an outermost position wherein it does not engage said contacts.

In testimony whereof I have hereunto set my hand this 6th day of August, 1930.
